MULTIPLE WAY INVERSE FEED-BACK CONNECTION

Eugen Leuthold, Neuhausen, Switzerland

Application August 1, 1951, Serial No. 239,714

Claims priority, application Germany August 10, 1950

3 Claims. (Cl. 179—171)

This invention relates to a multiple path inverse feed-back connection and is especially applicable to high frequency resonant circuits as they are used in radio receivers for example. In its more general aspects, the invention mainly consists in the compensation of certain phase displacements which, when present, adversely affect the resonance curve of the resonant circuits. It is, therefore, the main object of the invention to improve the shape of the resonance curve by eliminating such phase displacements and, incidentally, to thereby improve the sound transmitting properties of the radio receiver.

In the multiple path inverse feed-back circuits which have been known up to the present it has been found, that the resonance curve of tuned high or intermediate frequency amplifier stages attains a substantial slope simultaneously with increased band width thereof. It is, consequently, the most important object of the present invention to provide an amplifier circuit having a resonance curve of substantially rectangular shape.

In order to comply with this requirement as far as possible, very small inverse feed-back impedances have to be employed. However, these impedances have the disadvantages that asymmetries thereof will appear when capacitative or inductive, that is, non-resistive inverse feed-back impedances are used. As a consequence the resonance curve also becomes asymmetric, which causes distortions and, in extreme cases, even causes a tendency to oscillate.

In order to eliminate these difficulties and to produce a broad resonance curve having steep sides, the invention mainly consists of the compensation of adverse phase displacements or shifts of the current in relation to the generating inverse feed-back voltage by the employment of impedance elements which are connected to produce phase coincidence. The invention thus provides the necessary phase coincidence by compensating for the adverse phase displacements or shifts of the current in relation to the inverse feed-back voltage, which are introduced by the interaction of the capacitative and/or inductive impedances as well as the resistive impedances in the amplifier circuit. This phase coincidence and correction is produced by the employment of impedances such as are capable of achieving this result.

The adverse phase displacements or shifts of the occurring currents in relation to the respective inverse feed-back voltage can hereby be suitably compensated by the use of a phase-reversing circuit, to be explained more fully hereinafter, which is connected in parallel and/or in series with capacitative and/or inductive impedances.

A further feature of the invention resides in obtaining the required phase coincidence by an additional path of inverse feed-back consisting of a phase-reversing circuit applied to a point of inverse feed-back voltage of more than 90° displacement. Preferably a phase displacement of 180° will be imparted to the inverse feed-back voltage.

A further modification of the present invention consists in procuring the symmetry of the inverse feed-back

2

currents in a phase bridge using purely resistive feed-back impedances.

The invention will now be described with reference to the accompanying sheet of drawings, in which several modifications are illustrated by way of example.

Fig. 1 illustrates a known type of multiple path inverse feed-back circuit;

Fig. 2 shows a circuit in accordance with the invention with an additional inverse feed-back;

Fig. 3 shows a modified embodiment of the invention in which purely resistive impedances and a phase bridge for the additional inverse feed-back are used; and

Fig. 4 is a vector diagram for explaining the phase relationships of the voltages and currents in the feed-back circuits of the present invention.

In Fig. 1 a known form of the multiple inverse feed-back circuit is shown, in which an inverse feed-back is produced in the two circuits 1 and 2 by the resonant circuit 3, whereby all circuits are controlled with a single tube 4. One inverse feed-back path leads from the resonant circuit 3 through the resistance R_2 to the resonant circuit 2, and another inverse feed-back path through the condenser C_1 to the resonant circuit 1.

Fig. 2 illustrates a multiple path inverse feed-back connection in accordance with the present invention in which an additional inverse feed-back path is introduced in the resonant circuit 1, which leads to this circuit through an inductor L_1 thereby causing a voltage which is in opposite phase to the feed-back voltage caused by capacitor C_1 .

A further embodiment of the invention is shown in Fig. 3. In this figure, a first inverse feed-back path leads in known manner to the resonant circuit 2 through the resistance R_2 . In addition, a second inverse feed-back path leads to the resonant circuit 1 by means of a phase bridge $C—R—C—R$, consisting of capacitors C and resistors R , and by means of resistor R_1 . It is apparent that the resonant circuit 1 of Figs. 2 and 3 is a tuned circuit which appears in the output stage of the amplifier preceding the amplifier circuit incorporating the present invention.

In both embodiments of the invention as shown in Figs. 2 and 3 all the circuits are controlled by only a single tube 4.

Referring now to Fig. 4 and to Fig. 2 to which it refers, the feed-back voltage across resistor R_2 in the feed-back branch leading to tuned input circuit 2 is represented by vector E . For optimum performance it is desirable that the feed-back of energy to the tuned output circuit 1 of the immediately preceding stage be precisely 90° out of phase with the energy fed back to the tuned input circuit 2. It might appear that this could be accomplished merely by using a capacitive feed-back path. However, because of the resonant resistance (R_1) of tuned circuit 1, the voltage across capacitance C_1 has a phase relationship relative to E as illustrated by the vector E_{C_1} and the voltage across "resistor" R_1 is E_{R_1} . The current through capacitance C_1 leads the voltage thereacross by 90° as indicated by the dashed line vector I_{C_1} .

The voltage E across the inductive branch of the feed-back path is also broken up into two components, E_{L_1} across coupling coil L_1 and E_{R_1} across the "resistor" R_1 . These vectors are indicated in Fig. 4. The current through coupling coil L_1 lags the voltage thereacross by 90° and is indicated on the vector diagram by the dashed line I_{L_1} . As the inductive branch of the feed-back path is supplied to one end of the coil inductively coupled to tuned circuit 1 and the capacative branch to the other end of this coil, current vector I_{L_1} may be indicated by a second vector I'_{L_1} which is 180° out of phase with I_{L_1} .

As can be seen from the attached vector diagram in Fig. 4, the resultant of current vectors I_{C_1} and I'_{L_1} is a

current I indicated by vector I which is precisely 90° out of phase with the voltage across resistor R_2 and therefore the current through resistor R_2 .

The embodiments are shown in a diagrammatic form and as applied to only three circuits. It stands to reason that, without departing from the spirit of the invention, they may be applied with the same result to a greater number of circuits.

What I claim and desired to secure by Letters Patent of the United States is:

1. A circuit arrangement comprising, in combination, an amplifier stage having a tuned input circuit and a tuned output circuit; an additional tuned circuit coupled to said tuned input circuit for feeding energy thereto; a resistive first feed-back path from said tuned output circuit to said tuned input circuit for supplying a negative feed-back energy to said tuned input circuit; and means affording a second feed-back path from said tuned output circuit to said additional tuned circuit comprising coupling means coupled to the tuned output circuit, capacitive means defining one path portion between said coupling means and said additional tuned circuit, inductive means defining a second path portion between said coupling means and said additional tuned circuit, and means coupling an intermediate point between said first and second path portions to said coupling means for feeding energy to said additional tuned circuit which leads in phase the energy fed back by means of said first feed-back path to said tuned input circuit by precisely 90° .

2. A circuit arrangement comprising, in combination, an amplifier stage having a tuned input circuit and a tuned output circuit; an additional tuned circuit coupled to said tuned input circuit for feeding energy thereto; a resistive first feed-back path from said tuned output circuit to said tuned input circuit for supplying negative feed-back energy to said tuned input circuit, comprising a coil coupled to said input circuit and a resistor coupled between said output tuned circuit and said coil; and means affording a second feed-back path from said tuned output circuit to said additional tuned circuit comprising cou-

pling means coupled to the tuned output circuit, capacitive means defining one path portion between said coupling means and said additional tuned circuit, inductive means defining a second path portion between said coupling means and said additional tuned circuit and means coupling an intermediate point between said first and second path portions to said coupling means for feeding energy by said additional tuned circuit which leads in phase the energy fed back by means of said first feed-back path to said tuned input circuit by precisely 90° .

3. A circuit arrangement comprising, in combination, an amplifier stage having a tuned input circuit and a tuned output circuit; an additional tuned circuit coupled to said tuned input circuit for feeding energy thereto; a resistive first feed-back path from said tuned output circuit to said tuned input circuit for supplying negative feed-back energy to said tuned input circuit; and means affording a second feed-back path from said tuned output circuit to said additional tuned circuit for feeding energy to said additional tuned circuit which leads in phase the energy fed back to said tuned input circuit by precisely 90° , comprising means coupled to the tuned output circuit, a coil having a pair of input terminals and being coupled to said additional tuned circuit, capacitive impedance means coupling negative feed-back energy from said means coupled to the tuned output circuit to one of said input terminals, inductive impedance means coupling negative feed-back energy from said means coupled to the tuned output circuit to the other of said terminals, and means coupling an intermediate point on said coil to said means coupled to the output circuit.
